UNITED STATES PATENT OFFICE

WILLIAM M. GOLDSMITH, OF CINCINNATI, OHIO, ASSIGNOR TO THE GOLDSMITH METAL LATH COMPANY, OF CINCINNATI, OHIO, A CORPORATION OF OHIO

TILE AND SOFFIT MEANS FOR CONCRETE FLOOR CONSTRUCTION

Application filed July 17, 1929. Serial No. 379,022.

This invention relates to concrete construction and particularly to means for forming a ribbed floor structure.

An object of the invention is to provide means for forming concrete cross-ribs without the use of the usual temporary soffits, or cross bridging.

Another object is to provide such means which are adjustable, whereby varying sizes of ribs may be constructed by use of the same forming means.

Another object is to provide such forming elements which have means for bonding plastic material to the under surfaces thereof, such as in the formation of a ceiling.

These objects are attained by the means described herein and set forth in the accompanying drawings, in which:

Fig. 1 is a top plan view of a section of flooring before the application of the wet concrete. This view illustrates the use of the rib-forming elements of this invention.

Fig. 2 is a side elevational view of a tile or dome having the rib-forming means of the present invention attached thereto.

Fig. 3 is a view taken on line 3—3 of Fig. 2, part being broken away.

Fig. 4 is a view taken on line 4—4 of Fig. 2.

Fig. 5 is a view taken on line 5—5 of Fig. 2.

Fig. 6 is a cross sectional side view of adjacently positioned tiles, showing the rib forming means in operative position, parts being broken away.

Fig. 7 is a view similar to Fig. 6 showing a modification of the rib-forming means.

Figs. 8 and 9 are side elevational views of adjacently positioned tiles showing modifications of the rib forming means of this invention, parts being broken away.

Fig. 10 is a top plan view of an end portion of a tile showing another modification of the rib-forming element of the invention.

Fig. 11 is a detail view of one of the elements of the modification illustrated in Fig. 7.

Fig. 12 is a detail view of a modification of the element illustrated in Fig. 11.

This invention contemplates that type of construction in which spaced parallel rows of interfitting tiles or domes are supported upon open centering consisting of temporary wood

soffits. These soffits are positioned between parallel beams at right angles thereto. The tile rows are interrupted at regular intervals, and the open ends of the tiles, at these places, are closed by means of end closures fastened upon the tiles. Passages are thus provided, extending between the tiles transversely and longitudinally thereof, so that when concrete is poured over and around the positioned tiles, the plastic material enters into said passages and forms ribs crossing at right angles.

The temporary soffits upon which the edges of the tiles are supported extend in one direction, that is, at right angles to the beams, and these soffits, together with the side walls of the tiles serve to form or mold the concrete ribs running parallel with the tiles. The cross ribs are formed in the spaces occurring at intervals in the tile rows, and are molded by

the end closure plates on adjacent tiles and by short cross soffits extending between the longer soffits at right angles and in substantially the same plane therewith. Heretofore, it has been common to provide wood soffits for forming the cross ribs. This entailed a

considerable amount of construction work, which, by means of the present invention, is eliminated.

Moreover, by the use of means herein described both a large and a minute degree of adjustment of the soffits, is made possible. Another advantage arises in connection with the metal lath usually employed in this type of construction for forming ceilings. Sheets of this metal lath, are laid upon the open wood centering initially, and the ties are positioned upon the metal lath.

With reference to the drawings:

The tiles 15 have sides 16 and tops 17. The metal lath 18, as shown herein, is of the type displayed in the patent to M. S. Goldsmith, No. 1,168,627, and in applicant's co-pending application, Serial Number 127,149, filed

August 4, 1926, in which the lateral edges 22 of units of lath 18 are turned up for frictionally binding the sides of the tiles. End closures 19 close one end of the tiles 15, being secured thereto by means of ears 20 attached to closures 19 and bent backwardly against

sides 16 and top 17, to which they may be secured as by spot-welding 21.

End plates 23, preferably integral with closures 19, project forwardly from the base 24 of the closures, at substantially right angles therewith and in substantially the same plane as the bottom edges of tiles 15. The ends 25 of plates 23 protrude outwardly beyond the sides 16 of tiles 15. A dove tail 10 rib 26 extends longitudinally of the central portion of each plate 23. Rib 26 rises above the upper surface of plate 23 and is preferably formed by bending the material of plate 23 so that the opening 30 of rib 26 lies in the plane of plate 23, and is more restricted than the area enclosed by the body portion of rib 26, whereby a key formation results.

As shown in Fig. 1, the plates 23, in the positioned tiles, are adapted to be placed in opposed relation, their outer longitudinal edges overlapping, as indicated more clearly in Fig. 6, whereby a soffit is provided upon which concrete may be poured for forming a cross rib or beam. As will be seen in Fig. 1, the ends 25 of plates 23, have a firm bearing on the soffits 27 secured to beams 28.

By further reference to Fig. 6, it will be seen that a limited adjustment of the amount of overlap of plates 23 may be made. To 30 substantially increase the size or width of the cross rib or beam, and independent member or bridge plate 270 (Figs. 7 and 11) may be provided. Bridge plate 270 is formed similarly to plates 23, and of an equal length therewith and has side portions 280 with a dove tail rib 29 therebetween. As illustrated in Fig. 7, when it is desired to form a cross rib or beam of greater than the average size, the tiles are positioned so that a space intervenes between the outer longitudinal edges of the plates 23. Thereafter, the bridge plate 270 is positioned by placing the side portions 280 upon the similar portions of plates 23, so that the opening 30 provided by the rib 29, comes directly above the space separating the opposed plates 23. A greater amount of adjustment may be had in this type of soffit, due to the fact that the overlap of both portions 280 may be increased or decreased as desired.

In the modification shown in Fig. 8, a single soffit member 31 is substituted for the overlapping end plates heretofore described, said member 31 being attached to or integral 55 with the end closures 19 of two adjacent tiles. Spaced dove tail ribs 26 may be provided in the soffit member 31.

The modification in Fig. 9 provides for an independent soffit member 32 having its lateral edges upturned and doubled upon themselves to provide channel sockets 33. The bases 24 of end closures 19 are upturned to form flanges 34 adapted to be received in the channel sockets 33 of member 32. It is evident that member 32 may be of any desirable

width and be provided with one or more of the dove tail ribs 26.

As illustrated in Fig. 10, the soffit member 35 may be provided with a plurality of perforations 36, and the dove tail rib shown in the other modifications, omitted.

It should be noted that in all these modifications, a comparatively light metal may be used in constructing the soffit members, the dove tail rib serving the double purpose of stiffening the soffit members for bearing the load of concrete, and likewise, as explained, of affording bonding means for ceiling. In constructions where no ceiling plaster is to be applied to the under surfaces, of the soffits and consequently where no key shape or dove tail is required, any suitable cross soffit, such as that illustrated in Fig. 12 and having a suitable strengthening rib such as 290 (Fig. 12), may be provided. Cross soffits of this type may be formed either integral with or independent of the end closures previously disclosed herein.

Various other modifications along the lines herein described, will suggest themselves. For example, if the ceiling beneath a given floor is not to be plastered or is to be of the suspended type, any form of stiffening means other than the dove tail rib, may be used in the soffit members. Moreover, other suitable modes of attaching the independent soffit members shown in Figs. 7 and 9 to the closure bases 24 may be developed. Such other modifications, however, come obviously within the spirit and scope of this invention.

What is claimed is:

1. A tile for use in concrete floors and comprising top and side portions, a closure attached to the tile and closing one end thereof, a plate secured to the base of the closure, the ends of said plate extending outwardly beyond the sides of the tile, and means extending longitudinally of the central portion of the plate for bonding plastic material to the under surface thereof.

2. The combination with tiles adapted to be supported upon parallel soffits, of means closing the ends of the tiles, plates attached to the bases of the end-closing means at substantially right angles therewith and lying in the same plane as the bottom edges of the tiles, the ends of the plate being supported upon the parallel soffits, ribs extending longitudinally of the plates and providing means for bonding plastic material to the under surfaces of the plates, said plates being adapted to be positioned in spaced, opposed relationship, and independent members, having plate and rib structure similar to said plates and adapted to be positioned upon the outer portions of the plates for closing the space therebetween, whereby soffits are formed between the tiles.

3. Rib forming means for use with floor tiles for concrete construction, and compris-

ing end closures closing the ends of the tiles, plates attached to the bases of the closures and projecting outwardly therefrom at substantially right angles therewith, the tiles and plates being adapted to be spacedly supported upon parallel soffit members, and independent bridge members adapted to be positioned upon the outer portions of the plates for closing the spaces therebetween, both plates and bridge members comprising means for bonding plastic material to the under surfaces thereof.

4. Rib-forming means for concrete floor construction and comprising spaced tiles with end closures thereon, plate members adapted for horizontal positioning between the ends of the tiles, and complementary means on the plates and on the end closures for connecting said members whereby to close the space between the closures.

5. A tile adapted to be positioned upon parallel, horizontally-disposed support members, the tile comprising top and side portions, each side being disposed upon and extending longitudinally of one of said support members, an end closure secured to and closing an end of said tile, a plate member attached to the base of said closure and projecting beyond the end sides of the tile and supported upon said parallel support members, a dove-tail rib extending longitudinally of the upper surface of the plate and forming a depression complementary to the rib on the under surface of the plate, said plate being adapted to overlap or be overlapped by a similar member on an adjacent tile for providing a transverse soffit between the tiles.

6. The combination with a pair of tiles adapted to be supported upon spaced parallel soffits and to be disposed in spaced longitudinal alignment, of means closing the adjacently-disposed ends of the tiles, and a plate member having a strengthening rib thereon, said plate member being adapted to cooperate with the end closing means and to be supported upon the soffits for closing the space between the tiles.

7. Rib-forming means for concrete floor construction and comprising spaced tiles in longitudinal alignment and having end closures thereon, and plate members having strengthening means thereon, said members being adapted for horizontal positioning between the ends of the tiles and said strengthening means providing on both surfaces of the plate members a bonding formation adapted for interlocking relationship with plastic material placed on the plate members.

8. The combination of spaced soffits, a pair of tiles disposed in spaced longitudinal alignment, the tiles each comprising a top and sides, the sides of the tiles being supported on the soffits whereby the tiles close the spaces between the soffits and between the arms of

the tiles, means closing the adjacently-disposed ends of the tiles, and a plate member having its opposite ends supported on the soffits and closing the space between the soffits and the adjacently disposed ends of the tiles.

In testimony whereof, I have hereunto subscribed my name this 9th day of July, 1929.

WILLIAM M. GOLDSMITH.
